UNITED STATES PATENT OFFICE.

DANIEL L. ANTHONY, OF EL PASO, TEXAS, ASSIGNOR OF ONE-HALF TO H. E. COTTMAN, OF EL PASO, TEXAS.

BUTTONHOLE MAKER.

Application filed June 5, 1923. Serial No. 643,597.

This invention relates to an improved device for making button-holes with a sewing machine and resides in the provision of a simple, small and compact device of this nature which, in the form of an attachment, may be readily incorporated with various makes of sewing machines and operated in an efficacious manner.

One of the objects of the invention is the provision of an inexpensive device of the character described which will provide for the making of large quantities of button-holes in an expeditious manner at a comparatively low cost, the attachment of the device to a sewing machine not requiring the employment of skilled labor or the modification or changing of the construction of the sewing machine.

Another object of the invention is to provide a button-hole making attachment of the character described which may be readily adjusted in various ways to provide for making of button-holes of different sizes and kinds.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a perspective view of a part of a sewing machine showing the device of my invention as it will appear when attached thereto and in use.

Fig. 2 is an enlarged top plan view of a part of the device of the invention showing a piece of material with a button-hole thereto in as made with the device of the invention.

Fig. 3 is a sectional view taken on the line 3—3 of Fig. 2.

Fig. 4 is a longitudinal sectional view on the line 4—4 of Fig. 2.

Fig. 5 is a detail fragmentary longitudinal sectional view of the adjustable guide member.

Fig. 6 is a sectional view taken at right angles to Fig. 5.

The embodiment of the invention shown

in the accompanying drawing comprises a plate-like body 1, which in this instance is ovoidal in form but which may, however, be of any shape desired. The body has a peripheral circumferential groove 2 in which the material to have the button-holes made therein, as indicated by the reference numeral 3, is clamped by means of a clamping ring 4. The ring 4, in this instance, is made of a coiled helical spring having its ends joined to one another. The ring is stretched so as to surround the body portion and engage in the groove in order to clamp the cloth so that it is stretched tightly on the under side of the body portion. In the body portion there is provided a slot or opening 5 which permits access to the cloth in order to form the button-holes.

Provided in the body portion 1, is guide means generally designated 6, which means cooperates with guide means generally designated 7, the latter being attached to the presser foot stem 8 of the sewing machine 9, the presser foot, not shown, being removed in order to attach the means 7. The guide means 6 and 7 function so that the operator may take hold of the body portion and upon moving the same back and forth and in a circuitous path, the needle 9' will be caused to travel in the same direction and to sew the button-hole as indicated at 10, in Fig. 2.

The form of the guide means 6 in the present embodiment of the invention takes into consideration the provision of a slot or opening 11 in the body portion, which slot 11 is parallel to but spaced from the slot or opening 5. In the slot 11 there is removably mounted a block 12 provided with a longitudinally extending guide slot 13 divided longitudinally by a partition plate 14, the ends of which are suitably attached to the ends of the slot 13. The partition 14 is cut away adjacent its ends as at 15, so that there is provided a circuitous guide path for movement of the guide means 7. The body portion and block 12 have cooperating shoulders 16 and 17 which provide for supporting of the block in the body portion in flush relation to the upper and lower sides of the body portion. It will thus be seen that the guide means 6, as described, may be readily removed from the body portion and another guide element providing for a larger or smaller path, that is to say, of a different size as to the circuitous path, may be substi-

tuted in order to provide for a larger or smaller button-hole, as the case may be.

The guide means 7 illustrated in connection with the present form of the invention comprises a member simulating a presser foot in respect to a sleeve 18, which is adapted to receive the presser foot stem 8 upon removal of the ordinary presser foot, not shown. A set screw 19 in the sleeve provides for fastening the sleeve in place. Extending from the sleeve 18 is a plate 20 which has an opening 21 therein in which the needle 9' of the sewing machine operates. At the outer end of the plate there is provided a slot 23 in which a reciprocal guide lug 24 is mounted. The lug is removably held in place by a screw 25 and a washer 26, and the sliding movement thereof may be regulated by adjustable stop screws 27. The plate is arranged to slide over the top of the body portion and block 12 so that the guide lug will engage in the circuitous guide path provided by the means 6 carried on the body portion.

In the operation of the machine the cloth is clamped to the body portion as shown, so that the part in which the buttonhole is to be sewed is available through the opening 21 and slot 5. The operator adjusts the body portion by hand so that the guide lug 24 is disposed at one end of the slot 13 to one side of the partition 14. The sewing machine is then put into operation and the operator moves the body portion carrying the cloth back and forth while also advancing the body, lengthwise of the slot, keeping the guide lug in the space between one side of the partition and opposed wall of the slot. The guide lug 24 reciprocates and thus provides for the back and forth movement of the body portion and the work carried thereby at the same time that it provides for guiding the body in its lengthwise movement with respect to the guide slot 13. Preferably the guide lug is thin and has a flat face adapted to alternately engage the walls of the slot and the partition. By varying the thickness of this guide lug, the back and forth movement of the body portion may be varied and this will regulate the width of the stitching. This is continued until the opposite end of the slot is reached whereupon the operator manipulates the body portion so that the guide lug passes through the cut out portion 15 into the other side of the guide slot, and continues to move the body but in the opposite direction and back and forth at the same time, until the other cut out portion is reached, whereupon the body portion has been moved through a circuitous path and back and forth as well, while being so moved. This movement provides for sewing the circuitous wide stitch which provides the button-hole as shown in Fig. 2, and may be continued until the de-

sired amount of thread is sewed to the cloth to form a button-hole. By providing a thicker partition, the width of the line of stitching may be decreased and by providing a longer slot or changing the distance between the cut out portions, the length of the button-hole may be varied. The other adjustment provided for changing the characteristics of the button-hole is that effected by the stop screws 27 for the guide lug. From the foregoing it will be apparent that I have provided a small, compact and simply constructed button-hole making attachment which may be easily and effectively operated to provide in an expeditious manner and at low cost, a large number of button-holes.

By means of presser foot mechanism provided in the sewing machine, the guide means may be moved into and out of position cooperating with the guide means 6.

The guide lug 24, if stationary, would cause a space between the parallel lines of button-hole stitching such as would be objectionable and unsightly when the cloth was cut through between said rows. This space would be substantially equal in width to the combined thicknesses of the partition 14 and said lug. Thus, it will be seen that in permitting the lug to slide, this spacing of the parallel rows of stitching in the button-hole will be reduced to the minimum and by reason of the adjustment provided by the screws 27, the device may be made so that the stitching in the rows may overlap or may be spaced apart as desired, depending upon the material in which the button-hole is to be sewed. In certain kinds of material, the stitching tends to pucker or draw the material to the extent that in sewing the button-hole, provision must be made for larger cutting space between the rows of stitching.

The body member and guide means are such that a person unskilled in making button-holes may easily make button-holes of a uniform appearance.

The movement of the body portion is defined by the outline of the guide path formed by the guide means, except as to the back and forth movement, in a direction across the guide path.

I claim:

1. The combination with a sewing machine, of a cloth carrying member having an opening therein across which cloth is stretched, means for securing cloth to said member, said member being movable on the bed of a sewing machine to cause the needle to pass through the opening into the cloth and having a slot therein, a partition dividing the slot longitudinally, which partition is provided with recesses adjacent its ends, a member fixed to a part of the sewing machine adjacent the needle, and a guide lug carried by said member and loosely en-

gaged in said slot, which guide lug is capable of passing through the recesses of the partition.

2. The combination with a sewing machine, of a cloth carrying member having an opening therein across which cloth is stretched, means for securing cloth to said member, said member being movable on the bed of a sewing machine to cause the needle 10 to pass through the opening into the cloth and having a slot therein, a partition dividing the slot longitudinally, which partition is provided with recesses adjacent its ends, a member fixed to a part of the sewing machine adjacent the needle, and a guide lug carried by said member and loosely engaged in said slot, which guide lug is capable of passing through the recesses of the partition, said guide lug being reciprocally mounted 20 on the second named member.

3. The combination with a sewing machine, of a cloth carrying member having an opening therein across which cloth is stretched, means for securing cloth to said

member, said member being movable on the bed of a sewing machine and having a slot therein, a partition dividing the slot longitudinally and having recesses therein adjacent its ends and a guide member fixed to the sewing machine adjacent to the needle 30 and engaging loosely in said slot, said guide member being movable through the recesses of said partition and capable of reciprocating movement while engaged in said slot.

4. The combination with a sewing machine, of a member having an opening therein across which opening cloth is extended, means for attaching cloth to said member, said member being movable over the bed of a sewing machine and having an opening 35 therein adjacent the first named opening, a block removably mounted in the second named opening and having a guide path therein and a reciprocal guide member connected with a part of a sewing machine and 40 engaging loosely in the guide path.

DANIEL L. ANTHONY.
